UNITED STATES PATENT OFFICE.

CHARLES E. JONES AND CHARLES H. BILLINGS, OF CINCINNATI, OHIO,
ASSIGNORS TO C. E. JONES & BROTHER, OF SAME PLACE.

HUB-BAND.

SPECIFICATION forming part of Letters Patent No. 270,547, dated January 9, 1883.

Application filed October 13, 1882. (No model.)

To all whom it may concern:

Be it known that we, CHARLES E. JONES and CHARLES H. BILLINGS, of Cincinnati, Hamilton county, Ohio, have invented certain new and useful Improvements in Hub-Bands, of which the following is a specification.

This invention pertains to such hub-bands as have an inserted polished lining. The main band may be either polished or rough, for painting.

The invention relates to the form of the lining, which is such that it may be easily fitted to the interior of the main band and permit a fine finish with little labor.

15 A in the drawing, which shows a hub-band in section, is the main band, to be constructed usually of malleable cast-iron, and left unpolished.

B is a cup-shaped lining of very thin sheet metal, generally brass, highly finished on the parts which show when the band is in place on a hub.

C is the central hole in lining B, to permit the axle-nut to be gotten at.

25 F is a peripheral flange on front of cup B, covering the front edge of the rough band A.

E is the periphery of flange F, flush with surface of band A.

D is the solder uniting the parts.

30 The lining may be spun or struck from sheet metal, and, being somewhat elastic, will allow itself to form a tight spring fit in the rough interior of the main band, and the periphery E of the flange F permits itself to be spun into neat flush contact with the end of the band and produce a fine exterior finish, free from projections or cavities at the point E.

Hub-bands have been heretofore devised in

which a lining fitting within the main band had its peripheral edge or rim turned back so as to 40 lap upon the outer surface of the main band. Any uneven crack existing between the end of the main band and the front portion of the lining was thus covered up; but an undesirable bend was formed upon the front end of the 45 main band. We do not claim such bands as of our invention. We do not bend a covering of metal over onto the outside of the main band. Hub-bands have been devised in which a thick lining to fit inside and against the 50 main band had spurs cast upon it. After the main band was in place upon the hub the lining was driven into position and retained by the spurs engaging in the wooden hub. If a crack appeared irregularly around the frontal 55 joint, it could be remedied only by refitting the parts, and this joint-crack could never be suppressed, owing to the lining being fixed to the wooden hub instead of directly to the main band. The lining could shift independent of the main band, and the natural shrinkage of the hub would produce such shifting 60 constantly. We do not claim such bands as of our invention.

We claim as our invention—

65 The hub-band A, united by solder with the thin sheet-metal lining B, having opening C, and flush peripheral contacting frontal joint, E F, substantially as and for the purpose set forth.

CHARLES E. JONES.
CHARLES H. BILLINGS.
